INFLATABLE POOL COVER

Harold Perlman, West Covina, and Joseph Poltorak, La Puente, Calif., assignors to Spartan-Aqualon Corporation, South El Monte, Calif., a corporation of California

Filed May 6, 1968, Ser. No. 11,784

Term of patent 14 years

Int. Cl. D25—99

U.S. Cl. D13—1

FIG. 1.

FIG. 2.

FIG. 3.

FIG. 4.

FIG. 5.

FIG. 1 is a side elevational view of an inflatable pool cover incorporating our new design;

FIG. 2 is a top plan view thereof;

FIGS. 3 and 4 are end elevational views thereof; and

FIG. 5 is a perspective view of a modified form of the present invention, the only difference being that the top is of one color or material.

We claim:

The ornamental design for an inflatable pool cover, substantially as shown and described.
